GARMENT FINISHING APPARATUS

George W. Johnson, Cincinnati, Ohio, assignor
to The American Laundry Machinery Company,
Cincinnati, Ohio, a corporation of Ohio

Application February 14, 1946, Serial No. 647,506

3 Claims. (Cl. 223—73)

1

This invention relates to garment finishing apparatus, and more particularly to that type of apparatus in which the garment to be finished is dressed upon or around the outside of a hollow form, such as a canvas bag, into which steam or hot air is forced to cause it to pass outwardly through the garment and steam and dry the same.

One object of the invention is to provide an arrangement of this kind in which either dry steam, or air, or both, may be supplied to the garment.

Another object of the invention is to provide garment finishing apparatus of the kind described, in which the steam supply is so arranged as to prevent any possibility of water or moisture, such as condensate from the steam, being delivered to or upon the garment, and thus avoiding water spots or rough dry areas upon the same.

Another object of the invention is to provide a steaming device for garment finishing apparatus of the kind described, including a steam supply nozzle, together with a heated surface adjacent said nozzle and upon which any moisture or condensate is directed to thereby evaporate the same and prevent moisture, in the form of water or condensate, from reaching the garment.

Still another object is to provide a device of this kind in which the heater for evaporating condensate or moisture in the manner described, also serves as the means for heating the air current. Further objects of the invention in part are obvious and in part will appear more in detail hereinafter.

In the drawings, which represent one suitable embodiment of the invention,

Fig. 1 is a side elevation, with parts broken away near the bottom of the device to expose interior construction;

Fig. 2 is a sectional plan view on the line 2—2, Fig. 1;

Fig. 3 is a detail sectional elevation, on a larger scale, on the line 3—3, Fig. 2;

Fig. 4 is a detail sectional plan view, on the line 4—4, Fig. 3, showing a part of the damper; and

Fig. 5 is a detail view of certain valve controlling mechanism.

The finishing device shown in the drawings comprises a suitable base 10 designed to rest upon the floor or other suitable support and upon which is mounted a hollow casing 11 of any suitable shape in plan view, and shown as cylindrical, and the inner chamber 12 which communicates with the outlet 13 from a fan or blower 14

2

mounted on the base 10 and operated by a motor 15.

The upper end of the casing 11 supports a fixed sleeve or collar 16 provided with a series of circumferentially spaced openings 17, cooperating with a similar series of openings 18 in a sleeve-like ring 19 surrounding collar 16 and provided with an operating handle 20 projecting outwardly through a slot 21 in the casing wall. Ring 19 serves as a valve to control the flow of heated air as will later appear.

Mounted upon the collar 16, and removably held thereto by a split clamping ring 22, is a garment support 23, which may be of any suitable form or shape, sometimes roughly the shape of the garment, such as a shirt or coat, and which is shown as a simple bag, made of porous material, such as canvas or other fabric. The upper end of the bag is supported upon the upper end of a post 24, the lower end of which is carried by legs 25 mounted upon the top of a member 26. Member 26 serves both as a heater for the air supply and as a vaporizer for any possible water or condensate which might otherwise collect. It may be made of any suitable material, such as cast iron and, generally speaking, is of pail or dish form, having a base 27 secured to the base 10 and inner and outer walls 28, 29 joined at their upper ends and enclosing an annular chamber 30 surrounding the inner wall. Chamber 30 is provided with a connection to a steam supply, as by way of the pipe or conduit 31, and is provided with a drainage outlet pipe 32. Said chamber also communicates with a steam discharge pipe 33 provided with a valve 34 controlling the flow of steam to a suitable nozzle, such as a depending pipe 35 extending downwardly along the central axis of the inner chamber 36, closed at its bottom by cap 37 and provided with a series of small openings 38 which direct jets of steam outwardly against the inner wall of member 28. The floor of chamber 36 may be provided with a central raised portion 39 adapted to cause any liquid, such as water or condensate, which falls upon it from the nozzle 35 to flow outwardly over the floor of the chamber, and thus be more readily vaporized. The outer wall 29 is provided with heat transmitting fins 40.

Suitable means is provided for operating valve 34 such as a bell crank lever 41, shown in Fig. 5 as having one arm lying opposite the stem 42 of valve 34, and the other arm connected by a link 43 to a foot treadle 44. When the foot treadle is depressed the valve is opened, and said foot treadle, which is normally urged upwardly to-

ward valve closed position by a spring 45, may be releasably locked in its lower or valve open position by a latch dog 46 actuated by compression spring 47. Levers 44 and latch dog 46 are provided with foot plates 48, 49, respectively, enabling the operator to actuate them with his foot.

The apparatus described operates as follows:

Let it be assumed that a garment to be dried, such as a lady's dress, a man's shirt or coat, or any other garment, is dressed upon or over the bag form 23. Valves 19 and 34 are in closed position, but the motor 15 and fan 14 are in operation and steam is flowing through the supply pipe 31. Consequently member 28 is heated.

The operator may first open valve 19 to permit the flow of air from the fan to the chamber within the bag 23. Such air becomes heated by its passage through chamber 12 and along the heating fins 40 of member 28. The bag becomes distended in the usual manner.

Now the operator depresses foot treadle 44, opening valve 34 and causing the flow of steam from chamber 29 to the nozzle 35 and thence into chamber 36 from which it flows into bag 23 and outwardly through the garment dressed upon it. During this moistening period either steam alone or both steam and hot air, may be caused to flow through the garment.

When the garment is sufficiently moistened and the operator has straightened it out on the form, the latch dog 46 is actuated to release treadle 44 and permit valve 34 to close. Now heated air alone flows into the bag and through the garment, drying the same.

The steam supplied to the nozzle 35 flows outwardly from its orifices in jets directed against the inner wall of member 28 and is maintained at a temperature above boiling. But, if any water is present, or if moisture is formed in the way of condensate, such water or condensate is formed in chamber 36 and falls or is directed upon the inner surface of the wall thereof, thus being vaporized. As a consequence, only dry steam, without any moisture content, is delivered to the garment.

Of course, such condensate as would have time to collect in chamber 30 drains away from it by way of pipe 32, which usually communicates with an ordinary steam trap (not shown).

The construction described is a very efficient 50 garment finishing device and avoids any possibility of marring the quality of the work by the production of water spots or rough dry areas.

Other advantages of the invention will be apparent to those skilled in the art.

What I claim is:

1. Finishing apparatus of the character described, comprising a double walled dished member having an open top central cavity within its inner wall and an annular dish shaped closed chamber between its inner and outer walls, means

10 for circulating steam through said closed chamber, thereby to maintain said walls in heated condition, a steaming nozzle communicating with and supplied from the upper portion of said chamber and discharging into said cavity, and means for supporting a garment in distended form above said cavity, whereby steam discharged from said nozzle is delivered in dry form to the space within said garment.

2. Finishing apparatus of the character described in claim 1, in which the inner bottom

20 wall of said member has its upper surface sloping outwardly from its center, thereby to distribute over its heated surface and promptly vaporize any moisture or liquid which otherwise might tend to collect in said cavity.

3. Finishing apparatus of the character described in claim 1, in which the heated outer wall of said member is provided with heat radiating fins, and including means for conducting a stream of drying air past said radiating fins

30 and thence into the garment.

GEORGE W. JOHNSON.
